UNITED STATES PATENT OFFICE.

THOMAS F. CULLINAN, OF PROVIDENCE, RHODE ISLAND.

VENTILATING SYSTEM FOR MAUSOLEUMS.

Application filed October 4, 1926. Serial No. 139,478.

This invention relates to an improved construction of mausoleum which is provided for the reception of a plurality of bodies; and the object of this invention is to provide such a building in which the crypts or vaults are provided each with an inlet and a discharge ventilating opening.

A further object of the invention is to ventilate the interior of the building about 10 the bank of crypts or vaults.

The invention further consists in the arrangement of ventilating pipes whereby the discharging ventilating air from the body of the building will serve to induce, create or stimulate a discharging ventilating draft from the individual crypts or vaults.

A further object of the invention is to construct within the building a bank or stack of crypts or vaults the volume of which 20 bank or stack is less than that of the interior of the building, the crypts being spaced from the walls and the roof of the building and also having a ventilating area beneath the floor thereof, whereby a circulation of 25 air about the bank or stack of crypts or vaults is provided and a ventilating opening is arranged through the roof to permit escape of air circulating about the bank of the vaults.

With these and other objects in view, the invention consists of certain novel features of construction, as will be more fully described, and particularly pointed out in the appended claims.

In the accompanying drawings:

Figure 1 is a sectional view showing one arrangement of ventilating conduits for ventilating the building and each individual crypt therein.

Figure 2 is a view showing the ends of the vaults or crypts and the staggered arrangement of the intake and discharge openings to each crypt and to each vertical row of crypts.

Figure 3 is a plan view in section showing a portion of the building and the arrangement of the ventilating conduits for the different rows of crypts.

Figure 4 is a sectional side elevation 50 showing the downwardly turned intake tube leading through the wall of the crypt.

Figure 5 is a perspective view of this intake tube.

Figure 6 shows a short piece of tubing or 55 thimble screwed into the discharge end of

the intake tube for attaching the screen thereto.

Figure 7 is a detailed view of the screen which is connected to this tubing or thimble.

Figure 8 is a top view showing the general arrangement of the air ventilating discharge conduit leading from the different crypts to a common discharge opening.

Figure 9 is a modification showing a plan view partly in section with the crypts arranged in groups.

It is found in the practical construction of mausoleums necessary to provide a proper and complete system for ventilating the interior of the building as a whole and also for ventilating each individual crypt or vault and to so arrange the ventilating tubes or conduits as to set up a circulation of air in each crypt and to conduct and finally discharge this air out through the roof of the building. It is also found of advantage to provide a circulating system in which the discharge ventilating of air from the building proper will serve to induce or stimulate a circulating action of air through the individual crypts; and the following is a detailed description of the present embodiment of my invention showing one construction and arrangement of conductors therein by which these advantageous results may be accomplished:—

With reference to the drawings, 10 designates the floor of my improved mausoleum below which is formed an air space 11 of considerable size. This building is provided with walls 12 which are arranged to support the roof 13.

Supported on the floor of this building is a plurality of groups or stacks of crypts or vaults 14 arranged into vertically-disposed rows with a space 15 between the rows or groups to serve as a hall, corridor or chapel and those on opposite sides being connected at the top with a wall or cover 16 and at the bottom by the floor 10.

In addition to the ventilating space below the floor both the sides and ends of a stack or group of crypts are spaced from the outer walls 12 of the building leaving vertically-disposed ventilating channels 17. The floor at the bottom of these channels is provided with openings 18 which are arranged to communicate with the space 11 below the floor and the top 19 of the stack or group of crypts is spaced below the under surface of 110

the roof a short distance leaving an air space of relatively large size there.

The top 16 which connects the opposite spaced rows of crypts is provided with a 5 ventilating opening 20 from the hall or chapel into the upper chamber 22.

The lower side walls below the floor 10 are provided with ventilating openings 21 to permit entrance of outside air into this space 10 11 below the floor.

In order to create a ventilating draft upward about each stack or group of crypts, I have inserted a ventilating tube 23 in the roof to communicate with this upper 15 chamber 22 so that the air entering through the openings 21 in the lower space or cellar will rise about the crypts and be discharged at 23 through the roof thereby carrying off all objectionable odors.

20 In order to cause a circulation of air in each crypt or vault, I have provided a downwardly-turned flaring mouthed tube 24, the inner end of which extends through the end wall 25 of its crypt adjacent the upper portion 25 of the crypt the discharge end being turned downward and into this end of the tube is screwed a thimble 26 having a screen 27 over its end to prevent the entrance of foreign objects into the crypt.

30 Near the lower portion of each crypt on the same end as the inlet, I insert an air discharge tube 28 which leads directly upwardly from the crypt and into a horizontally-disposed header pipe 29 located in the upper chamber 22 of the building.

The inlet and outlet openings of each crypt are preferably staggered laterally with respect to each other and also the inlet tubes in the different crypts in each vertical 40 row are set staggered relative to each other so that these downwardly turned air intake tubes thus arranged will offer the minimum amount of interference one with the other to disturb the upward flow of ventilating air past the ends of the crypts.

45 To this header 29 is connected the main discharge conduit 30 which communicates therewith through the connecting pipes 31, one arrangement of which is best illustrated in Figure 8.

The upwardly extending discharge tube 30 is of a diameter less than that of the discharge tube 23 into which it extends preferably to a height less than that of the tube 23 so that the discharge flow of each tube will assist that of the other.

50 In some instances, it is found that the heat of the sun on the roof 13 serves to heat the air chamber 22 below the roof during the day and at night as the outside air cools, this heated air in the chamber is caused to rise and is discharged through the tube 23. This upward current of heated air serves to assist in setting up a discharging draft through the inner tube 30 whereby

a circulation of air is set up in each of the crypts to nicely ventilate the same.

By my improved construction of mausoleum the same is well ventilated and the objectionable odors are conducted out through 70 the discharge opening to be deposited in the outside air.

In some instances, where larger buildings are employed, the crypts or vaults may be arranged in spaced groups as illustrated in 75 Figure 9, in which the spaces 32 between the inner ends of the stack of crypts is employed as a ventilating channel to communicate with the space beneath the roof and from which the crypts receive their ventilating air as it passes upwardly from the space below the floor.

Having thus described one illustrative embodiment of my invention and the best mode known to me for carrying out my 85 method, I desire it to be understood that altho specific terms are employed, they are used in a generic and descriptive sense and not for the purpose of limitation, the scope of the invention being defined and limited 90 only by the terms of the appended claims.

I claim:

1. A mausoleum having a floor and a ventilating air space beneath the floor open to the outer air, side walls, a roof supported by said walls and having a ventilating opening, and a stack of crypts or vaults within the building having a combined volume less than that of the interior of the building and spaced from said walls and roof, means for venting said crypts, and means whereby the air entering the space below the floor is caused to flow upward about said stack into the space above and thence out through said roof opening to induce a draft through said crypt venting means. 100

2. In a mausoleum, a floor having a space beneath open to the outer air, side walls, a roof supported on said walls and a stack of crypts or vaults within the walls of a combined volume less than that of the interior of the building and spaced from said walls and roof, said roof having a ventilating opening in the roof communicating with the space below it, a ventilating conduit leading from each individual crypt, a main conduit communicating with said individual conduit and being smaller than and extending out through said roof opening and so arranged that the discharging draft of 105 one opening will assist that of the other. 115

3. In a mausoleum, a floor having a space beneath open to the outer air, side walls, a roof supported on said walls and a stack of crypts or vaults within the walls of a combined volume less than that of the interior of the building and spaced from said walls and roof, an air discharge tube in the roof communicating with the space below it, a 125 ventilating conduit from each individual

crypt, a header conduit communicating with said individual conduits, a main discharge conduit communicating with said header and extending into and spaced from said 5 roof tube whereby an exhaust draft through said roof stimulates a draft through said crypt discharge tube.

4. In a mausoleum, a plurality of crypts or vaults, each having an air inlet opening 10 adjacent its upper portion and an air discharge opening adjacent its lower portion.

5. In a mausoleum, a plurality of crypts or vaults, each having an air inlet opening adjacent its upper portion and an air discharge opening adjacent its lower portion, 15 said openings being provided with screens to exclude foreign matter.

6. In a mausoleum, a plurality of crypts or vaults, each having a ventilating air inlet 20 opening near its upper portion, a conductor communicating with said opening widely flaring at its receiving end and said crypts having an air discharge opening near its lower portion.

25 7. In a mausoleum, a plurality of crypts or vaults, each having a ventilating air inlet opening near its upper portion, a conductor communicating with said opening widely flaring at its receiving end and said crypts 30 having an air discharge opening near its lower portion, said air inlet and outlet to each crypt being disposed out of vertical alignment with each other.

8. In a mausoleum, a plurality of crypts 35 or vaults, each having a ventilating air inlet opening near its upper portion, a conductor communicating with said opening widely flaring at its receiving end and an individual air discharge conduit communicating with 40 the lower portion of each crypt.

9. In a mausoleum, a plurality of crypts or vaults, each having a ventilating air inlet opening near its upper portion, a conductor communicating with said opening, and an 45 individual air discharge conduit communi-

cating with the lower portion of each crypt and leading upward into a common discharge conduit.

10. In a mausoleum, a bank of crypts or vaults arranged in vertically and horizontally disposed rows, each vault having an air inlet conductor near its top and an air outlet conductor near its bottom portion, said inlet conductors to the vertical row of vaults being disposed in staggered relation to each 50 other.

11. In a mausoleum, a group of crypts or vaults arranged in vertically and horizontally disposed rows, each vault having an air inlet conductor near its top and an air outlet conductor near its bottom portion, 55 said inlet conductors to the vertical row of vaults being disposed in staggered relation to each other with a downwardly-turned receiving opening and an upwardly turned discharge conductor leading from its lower portion.

12. In a mausoleum, a plurality of crypts arranged in stacks and each crypt in the stack having a ventilating opening in its 60 end wall, and a vertically-disposed air conducting channel extending along the ends of the stack of crypts to supply the crypts with air.

13. In a mausoleum, a plurality of crypts arranged in stacks and each crypt in the stack having a ventilating opening in its end wall, a vertically-disposed air conducting channel extending along the ends of the stack of crypts to supply the crypts with air, 65 70 a roof on the mausoleum, said stack of crypts being of a height less than that of the roof forming an air space therebetween having a vent extending through the roof, and said air conducting channel communicating with the outside air at its lower end and with said vent at its opposite end. 85

In testimony whereof I affix my signature.

THOMAS F. CULLINAN.
